YORK.

APPARATUS FOR TREATING ORES OR THE LIKE.

1,379,083.

Specification of Letters Patent. Patented May 24, 1921.

Application filed April 10, 1919. Serial No. 289,061.

To all whom it may concern:

Be it known that I, GALEN H. CLEVENGER, a citizen of the United States, residing at Washington, in the District of Columbia, have invented certain new and useful Improvements in Apparatus for Treating Ores or the like, of which the following is a specification.

This invention relates to apparatus for 10 the heat-treatment of ores or other materials. More particularly, the invention has to do with furnaces for continuously treating ores under precisely regulated conditions of temperature, reduction, oxidation, 15 etc.

While the furnace of the present invention is useful for a variety of operations, its special application is in the carrying out of the process of treating ores containing 20 oxids of manganese described in a copending application filed by myself and M. H. Caron on Sept. 23, 1918, Ser. #258,888, and in Patent No. 1,298,454, granted March 25th, 1919, to said M. H. 25 Caron.

According to the aforesaid process, the reduction of the manganese oxids in the ore is required to take place under carefully regulated conditions and with cooling of the deoxidized or partially deoxidized ore in such manner that material reoxidation is avoided.

The furnace of the present invention is so constructed that the ore can be continuously treated according to the process referred to under precisely controlled conditions of temperature, reduction, etc., both in the furnacing step *per se* and in the subsequent cooling operation.

40 The invention will be further described in connection with the accompanying drawings, wherein:

Figure 1 is a diagrammatical plan view of one type of furnace embodying my improvements;

Fig. 2 is a diagrammatical side view of the same, partly in section;

Fig. 3 is an end view and Fig. 4 a section of the stuffing-box connection between 50 the rotary part of the furnace and the stationary discharge housing;

Fig. 5 is a section and Fig. 6 an end view

of the coupling which joins two dissimilar portions of the kiln or furnace;

Fig. 7 is a section of the kiln along the line 7-7 of Fig. 2;

Fig. 8 is a sectional view showing a pyrometer tube and the manner in which it is mounted in the furnace;

Fig. 9 and Fig. 10 show in section stuffing-box connections between the air pipe and certain stationary parts of the apparatus;

Fig. 11 is a sectional view through one of the sampling-tubes of the kiln; and

Figs. 12 and 13 are sectional views, in cross-planes, of a burner located near the lower or foot end of the furnace.

Referring to Figs. 1 and 2, the furnace 1, shown as an inclined kiln, is supplied with the ore or other material to be treated at its head or upper end from a hopper or the like 2 by means of suitable conveying mechanism 3. The end of the kiln extends into a flue 4 connecting with a stack 5. The enclosed conveyer 3 carries the ore across the flue and deposits it under regulation within the kiln, preferably in a bed of substantial depth. Discharge of the ore from the elevated end of the furnace is prevented by a circular ring or plate 6 on the end of the furnace, having however a central opening large enough to accommodate the casing of the conveyer and to permit free efflux of the gases from the kiln.

The lower end or foot of the furnace extends into a discharge chamber 7, being rotatably mounted in the front wall thereof through the intermediary of the packed joint 8 shown in detail in Figs. 3 and 4. As one of a number of suitable arrangements for effecting discharge of the ore from the kiln without admitting air thereto, the lower end 9 of the discharge chamber 7 is shown as submerged in a well 10 containing water or some solution and the treated material from the kiln is removed from the well 10 as it arrives from the chamber 7 by means of suitable conveying-means 11.

To the top of the discharge chamber 7 is connected a pipe or conduit 12 by means of which a gas may be supplied to the furnace from any suitable source. An air pipe 13 passes through the rear wall of the chamber 7, and is rotatably mounted therein

through the medium of a stuffing-box connection 14 such as that illustrated in Fig. 9. A pipe 15 leading from a blower or other supply of air is connected with pipe 13 through the agency of a suitable packed joint 16, such as is illustrated in Fig. 10, in such manner that the portion 13 of the air pipe can turn freely with respect to the stationary supply-portion 15 of the air pipe without 10 permitting escape of the air at the joint.

In Fig. 10, the stationary pipe 15 is shown as provided with a flange 17 secured to or integral with a thimble 18 to which is bolted in the well-known manner a gland 19 which presses against the packing 20. The packed connection 14 between the chamber 7 and the air-pipe 13 being quite similar to that of the coupling 16 and obvious in construction from Fig. 9, no further description thereof is thought necessary. A suitable pedestal 21 may be provided to assist in the support of the air-pipe, and it may be integral with the female member 18 of the stuffing-box as indicated in Fig. 10. Within the kiln the air-pipe may be supported in position by one or more spiders 22.

The rotary kiln shown by way of illustration only, is provided at intervals with the customary removable tires 23 whereby the furnace is rotatably supported upon pairs of roller-bearings 24. Rotation of the furnace may be effected in any suitable manner, the means shown comprising a removable circular rack 25 and a pinion 26, the latter receiving rotary movement through gearing or the like 27 from any suitable source of power.

The kiln proper comprises two sections, an upper lined section 28 including the greater part of the length of the furnace and a shorter unlined section 29 at the discharge end.

As indicated in section in Fig. 7, the upper portion 28 of the furnace comprises an outer shell 30, a fire-brick lining 31 and an intermediate lining or layer 32 of kieselguhr or the like. The shell 30 may be provided with additional heat-insulating means if desired. Radially protruding bricks or ore-lifters 33 extend longitudinally of the furnace throughout the length of its lined section except at its extreme upper end where the ore-feed screw 3 is located.

The lined and unlined sections of the furnace are joined by any suitable connection 34. The coupling shown, for example, in detail in Figs. 5 and 6 comprises a metal ring 35 secured to the lined section of the kiln by means of a flange 36 held fast between the shell 30 and a shoulder in the refractory lining 32, and a circumferential band 37 secured to the metal unlined section 29. The band 37 is provided with an annular flange or collar 38 which engages the outer face of the ring 35. A series of bolts

39 are secured at one of their ends in the ring 35 and extend, when the parts are assembled, through apertures in the collar 38 to receive at their opposite ends nuts or other securing means 40. In order to take care of expansion and consequent relative movements of the parts, springs 41 are interposed between the nuts 40 and the face of the collar 38.

From the standpoint of ore-treatment, the furnace may be considered as comprising three divisions or zones: (1) the preheating zone; (2) the reducing zone, and (3) the cooling zone. These zones are roughly indicated in Fig. 2 of the drawings by the letters A, B and C, respectively.

Mounted in the furnace at intervals in the reducing zone B are pipes 42, connected at their outer ends with an extension 43 (Figs. 1 and 13) of the air pipe 13 and bent at their inner ends toward the feed-end of the furnace to form a series of spaced air-jets 44. The exterior portion of the pipes 42 are provided with suitable valves 45 for controlling the air-supply to the jets and the tubes 46 are held in fireproof plugs 47 presently to be described in detail in connection with a particular jet. The extension 43 of the air-pipe is connected with the axially disposed portion 13 of the air-pipe by a joined short pipe 47 (Fig. 2) or other suitable connection passing through the wall of the furnace at a point approximately where the reducing and cooling zones join.

One or more of the jets near the end of the reducing zone, preferably the lowermost, is provided, as shown in Figs. 12 and 13, with a hood 48 which surrounds the opening of the jet 44. The rear wall of the hood which may be integral with the jet-pipe is provided with an annular series of openings 49. A point of localized higher temperature which insures constant ignition of the gas at that point is established near the end of the reducing zone by the burner, and the latter is regulated as to the amount of reducing gas passing to the same by an angularly adjustable, perforated, register-plate 50 mounted on the jet against the rear wall of the hood.

In Figs. 12 and 13 is also shown one arrangement whereby the jet-pipes 42 are mounted in the furnace. The outer part of each pipe is formed or provided with a laterally extending plate 51 which is bolted or otherwise secured to the upper face of a boss-plate 52, the under surface whereof conforms to the curved surface of the furnace-shell 30 to which it in turn is fastened. An annular sleeve 53 extends inwardly from the plate 51. The sleeve 53 preferably increases in thickness toward its inner end and its outer face conforms in shape to and fits snugly against the inside of the opening 54 in the furnace wall. This opening is shown 130

as oval in cross-section, but it may be circular or polygonal. The sleeve 53 due to its increasing thickness thus forms about the pipe 42 a tapering pocket and this pocket is 5 packed with a suitable cementitious fire-proof filling 55. To assist the sleeve 53 in maintaining the filling in place, a flange or key 56 may be formed on or secured to the pipe 42. The connections between the air-pipe extension 43 or the valved sections 57 and the pipes 42 are preferably separate from the pipes 42, as shown in Figs. 12 and 13, and are secured to the latter by, for instance, screw-bolts 58 which engage the 15 plates 51.

At intervals along the reducing zone of the furnace, I provide suitable sampling-tubes 59, Figs. 2 and 11, to facilitate ascertaining of the condition of the material being treated as it progresses through the kiln. The sampling-tubes are carried by collars or the like 60 to which they may be welded, and the tubes are held in place in suitable openings in the furnace wall by the collars 20 which are secured to the shell 30 by convenient means such as bolts 61, the under sides of the collars being concave to fit the cylindrical curvature of the shell 30.

A series of steel pyrometer tubes 62 (Figs. 30 2 and 8) carried by screw-plugs 63 are also provided at intervals along the furnace. The tubes extend a suitable way into the furnace through openings 64, being held in position by engagement of the threads of 35 the plugs 63 with corresponding threads in the shell. These tubes may be connected up in the well-known manner with a pyrometer when it is desired to ascertain the temperatures at any of the various points.

40 In operating the furnace, the speed of rotation and the inclination of the kiln are so adjusted as to insure the proper depth of ore in the bed and the progress of this bed in regulated manner through the kiln. 45 The ore is fed continuously into the upper end of the furnace, passes through the several zones A, B and C, successively, and is finally discharged at the lower end of the apparatus, cool and unsusceptible to atmospheric oxidation. A suitable reducing gas, such as producer-gas, is introduced through the pipe 12 and flows upward through the kiln in the direction opposite to that of the movement of the ore. Air is supplied 50 through pipes 15 and 13 to the jets 44 and the amount admitted to the kiln is regulated by the individual valves 45.

55 In the preheating zone A, the cold incoming material meets the hot waste gases from the reaction zone and these gases, which may be slightly reducing or neutral give up their heat to the material as it advances. When the furnace is properly operated, the material should be at the temperature necessary for reduction by the time

it reaches the reducing zone. In this zone any moisture in the material is driven off and are also any constituents volatile at the temperature of the zone.

In zone B where the greatest amount of 70 reduction takes place, it is necessary to supply the heat lost through radiation and through the endothermic reactions which occur.

This is attained in a precisely regulated 75 manner through progressive burning of the combustible gas brought about by the admission of air at intervals through the jets 44. The reduction may take place by this means at constant or decreasing or increasing temperature, regulated through the admission of air. In this zone, of course, the material reaches its maximum temperature.

In the cooling zone C, the sensible heat of the downwardly moving reduced ore or 80 other material is transferred in part to the entering gas and air. Such additional cooling as is required to lower the temperature of the reduced material below that at which it will reoxidize in the air is obtained by 85 radiation through the bare steel wall 29 of this section of the kiln. If necessary or desirable, the cooling may be augmented by one or more water-sprays playing on the shell.

90 It will be observed that the operation in my furnace proceeds under the counter-current principle. The cold incoming material is heated up by the waste gases until by the time it arrives at the zone B it is substantially at the reduction or reaction temperature. By controlling the individual air-jets, this temperature is maintained until the reaction has continued to the desired extent, by which time the material has 100 reached the entrance to the unlined cooling section of the furnace. The temperature of the treated material decreases in this section, its heat being transferred in part to the incoming reducing gas, until in a relatively cool condition it leaves the system 105 at the discharge end of the furnace. The cool gas coming from the producer or the like enters at the discharge end of the cooling section and becomes rapidly heated up 110 by the hot material which has been treated as it passes therethrough, until when it reaches the reaction zone it has attained a sufficiently high temperature to burn. Meeting at the localizing point of the burner 48 115 a limited amount of air, incipient combustion of the gas sets in, sufficient in degree or intensity only to maintain the temperature required for the reaction-conditions desirable at this point, without interfering with 120 the reducing action of the gas upon the material. As more air is supplied to the moving column of gas at the intervals where the successive air-jets are located in the zone B, the degree of combustion progresses until, 125

130

if desired, by the time the entrance to the preheating zone is reached, *i. e.* when it has passed the last burner or air-jet 44, complete combustion of all of the fuel-gas has been effected.

By such counter-current operation substantially all heat-losses are avoided and all the fuel values are used up. By maintaining the temperature in the reaction zone in 10 the manner described the time required for the reduction is reduced to a minimum.

The particular temperature maintained in the reaction zone varies with the character of the material undergoing treatment, the 15 rapidity of its progress through the kiln, etc., but in certain operations I have conducted with ores of the aforesaid character, I found that an ore-temperature of about 600° C. gave good results. The temperature 20 of the gas is of course somewhat higher than that of the ore.

While I have specifically described a rotary inclined kiln embodying my invention, it will be obvious that its application is not 25 restricted to this type of apparatus. It is equally applicable, for instance, to a multiple-hearth furnace of the McDougall type or any other type in fact wherein the material is caused to progress in its treatment 30 from one region to another.

Numerous changes can of course be made in the details of arrangement without departing from the spirit and scope of my 35 invention.

It will be understood that by the expression "reaction zone" as used herein, I intend to define the zone in which substantial heat-treatment occurs whether the process be one 40 of reduction or of oxidation or one in which the atmosphere is neutral.

It is also to be understood that the invention is not confined to the treatment of ores and the use of that term in the claims is not to be construed as a limitation to the scope 45 of its application.

Furthermore, it will be obvious that instead of having an arrangement like that shown wherein the preheating, reaction and cooling zones are integral, it is quite possible to have either the preheating section or the cooling section or both separate from the 50 reaction section. The cooling apparatus may be of the form of any of the standard types such as the Baker cooler.

I claim:

1. A furnace having a reaction zone through which material to be heated is moved progressively, means for passing a combustible gas through said zone and 60 means for progressively burning said gas.

2. A furnace having a reaction zone through which material is moved progressively, means for passing a combustible material through said zone and air jets at in-

tervals along said zone for controllably introducing air into said zone. 65

3. A furnace having a reaction zone through which material to be heated is moved progressively, means for passing a combustible gas through said zone counter 70 current to said material, means for igniting said gas adjacent the end of said zone toward which said material moves, and means at intervals along said zone for introducing gas capable of burning with said combustible gas. 75

4. A furnace for the progressive treatment of ores or other materials, having a preheating zone, a reaction zone and a cooling zone, and means at intervals in said reaction zone for controlling the temperature 80 therein.

5. A furnace for treating ores or the like, having an extended reaction zone, and means for variably admitting air at intervals along 85 said reaction zone.

6. A furnace for reducing ores or the like, having an extended reaction zone, means for passing reducing gas through said zone, and means for variably admitting air 90 at intervals along said zone.

7. A furnace for treating ores or the like, having an extended reaction zone, a plurality of air-jets arranged at intervals along 95 said zone, and means for independently controlling the admission of air to said jets.

8. A rotary furnace for treating ores or the like, having an extended reaction zone, a plurality of jet-pipes arranged to admit air at intervals along said zone and rotating 100 with the furnace, and means for independently controlling the admission of air to said jets.

9. A furnace for reducing ores or the like, having an extended reaction zone, means for introducing from without the furnace a reducing gas through said zone, and means arranged at intervals along said zone for 105 regula'bly effecting combustion of said gas therein. 110

10. A furnace for reducing ores or the like, having an extended reaction zone through which the ore is progressively moved, means for introducing a reducing gas at one end of the zone, and a plurality 115 of air-jets arranged at intervals along said zone to effect progressive combustion of the gas in said zone.

11. A furnace for reducing ores or the like, having an extended reaction zone 120 through which the ore is progressively moved, means for introducing a reducing gas at one end of the zone, a plurality of air-jets arranged at intervals along said zone to effect progressive combustion of the gas 125 in said zone, and means for independently controlling the admission of air to said jets.

12. A rotary furnace for reducing ores or

the like, having an extended reaction zone through which the ore is progressively moved, means for introducing a reducing gas at one end of the zone, and a plurality of jet-pipes rotating with the furnace and arranged to admit air at intervals along said zone to effect progressive combustion of the gas in said zone.

13. A rotary inclined furnace for reducing ores, or the like, having an extended reaction zone through which the ore is progressively moved toward the lower end, means for introducing a reducing gas at the lower end of the furnace, and a plurality of jet-pipes rotating with the furnace and arranged to admit air at intervals along said zone to effect progressive combustion of the gas in the furnace.

14. A furnace for the progressive treatment of ores or the like, having an ore-pre-heating zone, a reaction zone and a cooling zone, means for introducing a reducing gas through said cooling zone into the reaction zone, and means for variably admitting air at intervals along said reaction zone to effect progressive combustion of the gas.

15. A rotary furnace for reducing ores or the like, having a reaction zone and a cooling zone into which the ore progresses upon reduction, means for introducing a reducing gas into said cooling zone, and means for discharging the cooled reduced ore from the furnace without admitting air thereto.

16. A rotary inclined furnace for reducing ores or the like, having a reaction zone and a cooling zone into which the ore progresses upon reduction, means for introducing a reducing gas into the cooling zone, means for variably admitting air at intervals along said reaction zone, and means for

discharging the cooled reduced ore from the furnace without admitting air thereto.

17. A furnace for reducing ores or the like, having a reaction zone and a cooling zone into which the ore progresses upon reduction, a burner intermediate said zones, means for supplying air to said burner from the outside of the furnace and means for supplying reducing gas to the burner from within the furnace.

18. A rotary furnace for reducing ores or the like, having a reaction zone and a cooling zone into which the ore progresses upon reduction, means for introducing a reducing gas into said cooling zone, and a plurality of jet-pipes rotating with the furnace and arranged to variably admit air at intervals along said reaction zone, one of said jets near the end of the reaction zone having a perforated hood therearound to provide a burner into which some of said reducing gas passes.

19. A metallurgical furnace through which the material progressively travels, comprising a refractory-lined portion in which the substantial reaction occurs and an unlined cooling portion contiguous therewith.

20. A metallurgical furnace through which the material progressively travels, comprising a refractory-lined portion in which the substantial reaction occurs, means at intervals along the reaction section for variably admitting air to precisely regulate the temperature in such portion, and an unlined cooling portion contiguous with said lined portion.

In testimony whereof, I affix my signature.

GALEN H. CLEVENGER.
